UNITED STATES PATENT OFFICE.

GEORGE J. NOVIKOFF, OF PHILADELPHIA, PENNSYLVANIA.

HAND-GRENADE.

1,295,577.

Specification of Letters Patent. Patented Feb. 25, 1919.

Application filed February 23, 1918. Serial No. 218,816.

To all whom it may concern:

Be it known that I, GEORGE J. NOVIKOFF, a citizen of Russia, resident of Philadelphia, county of Philadelphia, and State of Pennsylvania, have invented certain new and useful Improvements in Hand-Grenades, of which the following is a specification.

This invention relates to improvements in projectiles and particularly to types known 10 as hand grenades.

The principal object of the invention is to provide a grenade in a form suitable to be thrown by hand and in a particularly convenient manner, a portion of the grenade 15 remaining in the hand.

A further object is to provide a grenade which will become automatically discharged or detonated upon striking a rigid or fixed object.

20 These and other like objects are attained by the novel construction and combination of parts hereinafter described and shown in the accompanying drawings, forming a material part of this disclosure, and in 25 which:

Figure 1 is a vertical sectional view taken through a grenade made in accordance with the invention, the section being taken substantially on line 1-1 of Fig. 5.

30 Fig. 2 is a fragmental side elevational view of the same, the view being taken in a different plan from Fig. 1.

Fig. 3 is a fragmentary sectional view similar to Fig. 1, but showing the parts in 35 a discharged position.

Fig. 4 is a top plan view of the grenade.

Fig. 5 is a transverse sectional view taken on line 5-5 of Fig. 1.

Fig. 6 is a transverse sectional view taken 40 on line 6-6 of Fig. 1.

Fig. 7 is a similar transverse sectional view taken on line 7-7 of Fig. 1, and

45 Figs. 8, 9, 10 and 11 are plan views showing the formation of the structural elements used in the charge carrying chamber prior to bending.

The invention comprises a rigid tubular stem or sleeve 15, having an annular enlargement 16, midway in its length, and 50 screw-threaded in its extreme upper end to receive the cap screw 17, provided with a central downwardly extending stem 18. An outer sleeve 20, is slidably engaged with the upper portion of the tubular stem 15, the 55 same being adapted to be grasped in the hand and having an enlarged flanged outer

end 21, preventing the outer sleeve from slipping through the hand at the moment it is discharged. This sleeve is normally held in operative position by means of a 60 bent flat spring 22, the same being made however, so that upon force being exerted, the spring will be depressed, allowing the outer hand sleeve 20, to readily slide over and separate from the main stem 15. 65

A hammer 24 having a rounded head 25, adapted to make contact with the projecting pin 18, is held in an inoperative position normally, by reason of the reduced neck 26, the same engaging with the bent end 27, of 70 another flat spring 28, rigidly engaged to the outer wall of the stem 15 by the screw 29, and passing through an opening appropriately formed in the stem.

At the lower end of the hammer 24 is engaged a thimble 30 holding a cartridge 31, which contains a high explosive or detonator 32, the purpose of which will be further on described. 75

The lower end of the stem 15, is screw-threaded to a plug 35, formed with a head or cap 36, containing a tubular nipple 37, having a conical point 38, through the sides of which extends a plurality of recesses 39, leading to the central cavity 40, which extends downwardly through the tube 41, into the body of the charge chamber as can best be seen in Fig. 1. 80

The charge chamber is formed in a peculiar manner, the same consisting of a central tubular element 44, containing a powder charge 45, and surrounded by a second powder charge 46, held in a triangularly sectioned chamber 47, embedded in another powder charge 48, contained in the hexagonal walls 49, surrounded by a third powder charge 50, arranged within the hexagonal walls 51 of another chamber embedded in the outer powder charge 52, carried in a circular shell or casing 53. 90

The upper ends of the plates 44-47 and 49 enter into a powder chamber 56, while the partition plate 51 contacts with the head 36. The outer circularly bent plate or casing 53 is crimped to engage with the heads 36 and held in place by a washer like cap plate 57, the lower of the casing 53 being formed with inturned edges 54, by means of which the lower or bottom cover 55 is held in place. 100

As will be noted in Figs. 8 to 11 inclusive, the several interior partition plates 44, 105

47, 49 and 51, are corrugated so as to be materially strengthened and which are adapted to fly into pieces when the powder charges adjacent thereto are exploded.

5 In operation, the implement being grasped by the outer sleeve 27, it is thrown with great vigor, so that the sleeve will depress the spring 22, permitting the grenade to pass into the air, whereupon the spring 28, 10 moves outwardly, permitting the hammer 24, to be freed.

Upon striking any fixed object the hammer 24, causes the detonating cap 31, to come into contact with the point 38, the flame 15 from the detonator 32 passing through the openings 39, 40 and 41 into the central powder compartment and through the powder compartment 56, causes all of the several powder charges to be exploded, in a manner 20 well understood.

Having thus described my invention what I claim as new and desire to secure by Letters Patent, is:

1. In a hand grenade, the combination 25 with a shank, a thimble movable thereon, said thimble being adapted to be grasped by the hand, means for normally maintaining said thimble on said shank, a hammer slidably contained in said shank, means for 30 normally maintaining said hammer in an inoperative position, means for permitting the freedom of said handle upon the release of said thimble, a plurality of powder charges carried in the body of the grenade, 35 a detonator carried by said hammer and means in the body of said grenade for distributing the sparks from said detonator.

2. In a hand grenade, the combination 40 with a body having a plurality of longitudinal partitions therein, powder charges distributed between said partitions, means for reinforcing said partitions, a hollow shank engaged with said body, a pointed element set in said body having openings communicating with said powder charges, a tubular shank engaged with said body, a hammer movable in said shank, a sleeve slidable on 45 said shank, means for normally holding said

sleeve in engagement, means for limiting the outward motion of said hammer, means for permitting said hammer to operate upon the sliding of said sleeve and a detonator carried by said hammer adapted to engage with said pointed element whereby the powder charges are exploded.

3. In a hand grenade, the combination 55 with a body having a plurality of powder charges disposed therewithin, a conical pointed nipple entering into said body and having a plurality of openings extending 60 outwardly therefrom, a shank rigidly engaged with said body, a sleeve slidable on said shank adapted to be operated by the hand, means for normally holding said sleeve engaged with said shank, a hammer movable in said shank, a spring whereby 65 said hammer is normally held in an inoperative position, said spring liberating said hammer when said sleeve is withdrawn, means for limiting the outer movement of 70 said hammer, and a detonating charge carried by said hammer, said detonating charge coöperating with said nipple.

4. In a hand grenade, the combination 75 with a body having a plurality of compartments formed therein, the partitions between said compartments being corrugated, a head affixed to said body, said head having a central projection, a nipple engaged with said head, said nipple having a plurality of 80 openings adjacent to its upper end, and terminating in a conical point, a shank rigidly engaged with the head of said body, a hammer movable within said shank, a manually operable sleeve slidable on said shank, means 85 for normally holding said sleeve in engagement, means on said shank whereby said hammer is released upon the operation of said sleeve, and a detonating charge carried by said hammer adapted to make contact with the nipple upon the contact of said body with a rigid object.

In testimony whereof I have affixed my signature.

GEORGE J. NOVIKOFF.
